UNITED STATES PATENT OFFICE

ROY CROSS, OF KANSAS CITY, MISSOURI

PROCESS FOR OBTAINING PHENOLS FROM COAL TAR DISTILLATES

Application filed May 2, 1925. Serial No. 27,491.

This invention relates to improvements in coal tar phenols and related compounds and a process of making the same, and refers more particularly to the production of coal tar phenols such as cresylic acid including such materials as meta-cresol, para-cresol and ortho-cresol and related compounds by the thermal decomposition of the coal tar and its heavier distillates at high temperatures and pressures.

Among the objects of the invention are, to provide a product and process in which is produced, by cracking or thermal decomposition, cresylic acid having a germicidal value greater than phenol and a product readily recovered by dissolving material from the distillate and recovered by neutralization of the solvent vehicle; to provide a product which, besides having a high germicidal value, is commercially important as a basis for dye stuffs, and, in general, to provide a product and process hereinafter described in more detail.

The single figure is a diagrammatic side elevational view of an apparatus adaptable for producing coal tar phenols of the character described.

Referring to the drawing, 1 is a furnace containing the preheating coil 2 and the heating coil 3. 4 is a reaction chamber; 5 is an evaporator; 6 is a bubble tower; 7 is a condenser, and 8 is a receiver. Unvaporized material withdrawn from the evaporator is reduced in temperature in a cooler 9 prior to being directed to storage.

Describing, briefly, the operation, the coal tar distillate to be treated is introduced through the charging line 10, controlled by a valve 11, and is forced by means of a pump 12 through a line 13, thence through the continuous coils 2 and 3 where it is brought to a cracking temperature and directed through the discharge line 14 to the reaction chamber 4. During its passage through the heating coils and reaction chamber, it is preferably maintained under cracking conditions of temperature and pressure controlled to effect cracking without substantial vaporization of the material being treated. On discharge 50 from the reaction chamber, pressure is re-

duced at the valve 15 and the highly heated products are discharged into the evaporator 5 where the volatile fractions pass off through the vapor line 16, while the unvaporized material is drawn off either continuously or intermittently through the line 17, controlled by the valve 18, which conducts the unvaporized products to the cooler 9 where, after cooling in the coil 19, the products are directed to storage through the discharge line 20. The overhead volatile material is subjected to a refluxing action in the dephlegmator 6, which is preferably of the bubble tower construction in order to more effectively separate out the fractions having a higher boiling range than those desired in the final distillate. The uncondensed vapors passing off from the top of the bubble tower are directed through the line 21 to the condenser coil 22 positioned in the condenser 7 and passed finally into the receiver 8 where they are collected as liquid distillate. This receiver is equipped with a liquid draw off line 23, regulated by a valve 24, and a gas line 25, controlled by a valve 26. The condensed or refluxed material collected in the bottom of the bubble tower is drawn off through the line 27, controlled by the valve 28, returned to be recycled with the charging stock by means of the pump 12. An auxiliary charging line 29, controlled by a valve 30, is connected into the line 11 for the purpose of supplying products containing the hydroxyl group such as glycols, glycerols and alcohol. With certain coal tars, it has been found advantageous to supply material of this character in order to increase the yield of phenols or cresylic acid in the final distillate. A bypass line 31, around the reaction chamber 40 and controlled by valves 32 and 33, furnishes a means for cutting out the reaction chamber when it is desired to operate under lower pressure and effect the conversion by pressure distillation as contrasted with the conversion described in which the cracking takes place without substantial vaporization or under excessive pressures preferably in excess of 350 pounds per square inch. The cracking of the coal tar distillates includes

pressures ranging from 50 to 1,000 pounds per square inch and temperatures of from 750° F. to 1,000° F. Normally, it has been found advantageous to operate at temperatures of from 800° F. to 950° F. during the reaction period and at pressures of from 600 to 1,000 pounds per square inch.

In the case of typical German coal tar having a specific gravity of 1.101 yielding an overhead distillate having a specific gravity of 1.007, this latter distillate utilized as charging stock and representing approximately one-half of the original coal tar, on being subjected to temperatures of 850° F. and 600 pounds pressure per square inch, resulted in a synthetic product having substantially thirty (30%) percent of cresols or cresylic acid soluble in caustic soda and approximately thirty (30%) percent of aromatic hydrocarbons. The specific gravity of a mixed product distilled from the synthetic oil at temperatures up to 437° F. had a specific gravity of 0.891, and initial boiling point of 125° F., while the cresols or portions of the product soluble in caustic soda solution had a specific gravity of 1.03. The specific gravity of this mixed product or distillate will normally not be less than .8 with a distillation range of from 125° F. to 450° F.

The preferred method of operation for the production of phenols or related products such as cresols is to subject the heavier coal tar compounds, preferably those produced by high temperature carbonization of coal, to temperatures above 800° F. and pressures in excess of 50 pounds per square inch. This is preferably done as described by passing the charging stock through a coil in a furnace into an expansion chamber or reaction chamber as shown at 4 in the drawings. Distillation subsequent to this cracking reaction may be either direct from the expansion chamber which may be carried on in the apparatus shown by by-passing the reaction chamber and utilizing the evaporator as the expansion chamber or the pressure may be reduced and distillation carried on from the expansion chamber 5 by a reduction of pressure between the reaction chamber and the evaporator,— the chamber 4 being used solely as the reaction stage. The heavy residue, as described, may be continuously or intermittently removed as pitch from the evaporator and a portion of the distillate, passing over at a higher temperature than 440° F. or thereabouts, is returned by refluxing to be retreated in a heating stage. As mentioned, it has also been found that the yield of phenols or cresols or their allied products may be increased by the addition of substances containing the hydroxyl group such as glycols, glycerols and alcohols. The largest yield is obtained from heavy coal tar which has been slightly oxidized or made from coal carrying considerable oxygen. It is probable that the

hydroxyl group in the heavier compounds forms the hydroxyl group of the cresols. If this group is not present in the heavier compounds, then it may be obtained by the addition of substances containing such groups from outside sources. The operation of decomposing the heavier coal tar compounds, including the distillation, fractionation, refining and bleaching may be carried out in a single plant by continuous operation without redistillation or reheating to produce a water-white cresylic acid or cresols of mixed composition.

The phenols or cresols, as described, are products of thermal decomposition which are substantially insoluble in water and soluble in a caustic soda solution; further, they have a specific gravity of at least one, and a normal distillation range of approximately 350° to 450° F. The coal tar phenols consists of the benzene nucleus with one or more hydroxyl groups. Phenols and their related compounds, produced as described, have a germicidal value greater than commercial phenol or carbolic acid as produced at the present time and according to the germicidal table issued by the United States Hygienic Laboratory under the Treasury Department, Washington, D. C.

To recover the phenols from the distillate, the latter is treated with a caustic soda solution which dissolves out the phenol, the latter being recovered by neutralization of the solvent vehicle with acid such as hydrochloric and sulphuric.

Besides being produced from coal tar compounds such as hereinbefore explained, phenols and their related products including cresylic acid and the like, may be produced as a by-product from certain petroleum hydrocarbons containing aromatic compounds or a benzene nucleus,—a typical oil being an oil of California type. When petroleum hydrocarbons are treated for their phenol content, the cresylic acid products would be by-products of a light motor fuel produced and recovered from the final distillate by dissolving out this material with a caustic soda solution similarly to the treatment of coal tar distillate.

I claim as my invention:

1. A process of producing coal tar phenols comprising the steps of adding an alcohol to a coal tar distillate, and then subjecting the distillate to cracking temperatures and pressures, condensing the evolved vapors, collecting the distillates, and recovering the phenols therefrom.

2. A process of producing coal tar phenols, comprising the steps of subjecting a coal tar distillate to cracking temperatures and pressures regulated to prevent material vaporization, releasing the pressure and distilling off the volatile fractions with the contained

heat of the oil, condensing the vaporized material and recovering the phenols.

3. A process of producing coal tar phenols, comprising the steps of subjecting coal tar distillate to temperatures ranging from 700° F. to 1000° F. and pressures in excess of 350 pounds per square inch, releasing the pressures and distilling off the volatile fraction, condensing the vaporized material and recovering the phenols.
